PROCESS OF HEATING FLUIDS AND APPARATUS THEREFOR

Joseph G. Alther, Chicago, Ill., assignor to Universal Oil Products Company, Chicago, Ill., a corporation of South Dakota

Application June 4, 1932, Serial No. 615,360
Renewed February 7, 1935

18 Claims. (Cl. 122—356)

This invention particularly refers to an improved method and means of heating fluids, during their passage through a fluid conduit, which comprises subjecting the maximum surface of the fluid conduit to high rates of heating in order to obtain a high average rate of heat input over the entire surface of the conduit.

More particularly the invention refers to a process for heating fluids wherein radiant and convection heat are applied to the fluid conduits to obtain a maximum average rate of heat input over the entire surface of the said conduit.

While the invention may be applied to the heating of fluids generally, it is particularly applicable to the heating of hydrocarbon oils and more particularly in the cracking of hydrocarbon oils.

Among the advantages of the present invention are: (a) Higher average heat input and more uniform intensity of heat application to the entire surface and periphery of the heating tubes than obtainable by ordinary methods with the same maximum heat input; (b) Flexibility of control of heat application to obtain any desired rate of heat input by direct control of the firing conditions; (c) High tube efficiency, i. e., increased capacity for a given tube surface or, vice versa, decreased tube surface for a given capacity as compared with conventional radiant and convection heating methods; (d) Quick heating of the fluid to relatively high temperatures with minimum time, with consequent reduction in overheating and overcracking when processing hydrocarbon oils, thus increasing the yield and octane number or knock rating of the gasoline product and reducing the gas formation and coke deposition in the tubes. Among the further advantages of the present invention are the reduction in the cost of installation, maintenance and operation and increased safety, due to the smaller equipment required, and to the minimization of internal stress in the tube walls, due to unequal heat distribution.

In heaters employing both radiant and convection heat which provide for the application of direct or nascent radiant heat energy from a source of heat to the fluid conduit or heating tubes from one direction only, the opposite sides of the tubes ordinarily receive some indirect radiant heat from adjacent reflecting surfaces, while the distribution of convection heat around the tubes is uncontrolled and varies with different furnace structure and tube arrangements as well as with variations in draft and other firing conditions in the furnace. Obviously this method gives unequal heating around the tube or fluid

conduit, the side exposed to direct radiation from the source of heat usually receiving heat at an average rate approximately twice as great as the average rate of heating on the opposite surface of the tube, which is exposed to reflected radiant heat, thus greatly decreasing the average rate of heat input, over the entire tube surface, below the maximum rate. Due to unequal heat intensity at different points around the circumference of the tube, the walls of the tube are subjected to unequal expansion stresses and, in the heating of hydrocarbon oils to the high temperatures required for their conversion, high local heat intensities often cause local overheating of a portion of the oil and the resulting formation of excessive quantities of coke and gas.

The present invention embodies a furnace in which the fluid conduit is heated from opposite sides by both radiant and convection heat in such a manner that the maximum surface of each tube of the fluid conduit is subjected to a high rate of heat input and uniform heating conditions are obtained on opposite sides of the tube. In this manner the average rate of heating over the entire tube surface may be greatly increased over that obtainable by other methods without increasing the maximum rate of heating. Thus a much higher tube efficiency is obtainable and the fluid undergoing heating may be heated to the desired temperature in a minimum of time. The simplicity and compactness of the furnace structure of the present invention, as well as the decreased amount of tube surface required for a given capacity, are obvious advantages. Also, due to more uniform heating of the tube, unequal expansion stresses are minimized, permitting higher maximum rates of heating than may be safely employed when high unequal expansion stresses are present in the tube walls. Uniform heating also eliminates local overheating of the fluid passing through the tube and results in the production of less gas and coke and in a motor fuel product of increased antiknock value, as applied to the conversion of hydrocarbon oil.

The attached diagrammatic drawing illustrates one specific form of apparatus designed to incorporate the features and advantages of the present invention. It should be understood that a specific form of apparatus is shown only for the purpose of more clearly illustrating the ease of incorporating the features of the invention in a simple furnace structure and that the invention is not limited to this nor to any other specific form of apparatus.

Referring to the drawing, Figure 1 is a cross-

sectional plan view. Figure 2 is a side elevation, showing a cross-section through the furnace taken along a vertical plane indicated by the line 2-2 in Figure 1. Figure 3 is an end elevation taken in cross-section on a plane indicated by the line 3-3 of Figure 1. Identical parts in the different views are given the same numerical designation. The outer furnace structure comprises side walls 1 and 1', end-walls 2 and 2', a roof 3 and a floor 4. Perforated distributing walls or baffles 5 and 5' separate the combustion compartments 6 and 6' from the heating compartment 7, which contains the fluid conduit. The combustion products pass through the perforations 8, in walls 5 and 5', into heating zone 7, from which they pass through the openings 9 in the floor 10 of the heating zone and through flue 11 to a suitable stack, not shown, or to a suitable air preheater, also not shown.

The fluid conduit, in the particular furnace structure here illustrated, comprises a single vertical row of horizontal tubes 12, which are connected in series by means of suitable headers or return bends 13 and have inlet and outlet ports 14 and 14', which are interchangeable so that the oil, or other fluid to be heated, may be passed through the tubes of the heating coil or fluid conduit in either an upward or a downward direction. It will be understood that vertically disposed tubes may be employed when desired, also that in either case the tubes may be connected either in parallel or in series and that many other modifications may be employed without departing from the spirit and scope of the invention.

The furnace may be fired with any desired form of fuel by means of suitable burners through firing ports 15 which, in the case illustrated, are located in the side walls 1 and 1' of the furnace. It will be understood that the furnace may, of course, be fired from either the top, ends or sides, or in any combination of these manners, although only side firing ports are illustrated in the drawing.

The perforated distributing or baffle walls 5 and 5' are preferably constructed of material of high thermal conductivity, such as fused or molded alumina or silica, artificial or natural mullite etc., able to withstand high temperatures and capable of assuming incandescence upon heating, or capable of radiating heat applied from combustion zones 6 and 6', into heating compartment 7. Radiant heat from the walls 5 and 5', as well as from the flame and/or hot combustion gases through ports 8 in these walls, is supplied to opposite sides of each of the tubes 12 of the fluid conduit and hot combustion gases, directed into heating compartment 7 through the perforations 8 of the walls 5 and 5', come into contact with opposite sides of the tubes 12 and supply additional heat thereto by convection.

By employing uniform firing conditions in combustion zones 6 and 6', the opposite sides of any tube 12 are heated equally. By regulating the intensity of firing through different firing ports in each of the side walls 1 and 1' of the furnace by means of independently controlled burner 16 of any suitable form, the heat intensity along wall 5 and 5' may be evenly distributed or may be varied along different horizontal portions of the walls, to suit requirements. In this manner the intensity of heating may be maintained uniform along the entire bank of tubes of the fluid conduit or different heating intensities may be employed in different portions of the fluid conduit, permitting a uniform rate of heating of the fluid undergoing

treatment through the entire heating coil or progressively increasing or progressively decreasing rates of heating as the fluid passes through the heating coil or, in fact, any desired type of heating curve may be obtained in the same furnace by regulating the firing conditions. Preferably when the intensity of heating along walls 5 and 5' is varied from top to bottom, as well as when a uniform intensity is employed over the whole surface of the walls, the heating conditions imposed on horizontally opposite portions of the two walls 5 and 5' are maintained substantially the same by employing equal firing in horizontally opposite firing ports in order to maintain uniform heating conditions on opposite sides of each individual tube 15 in the heating coil.

It will be understood that ordinary heating methods may be employed in conjunction with the methods of the present invention. For example, an additional bank of tubes of any well known form may be employed to recover additional fluid heat from the combustion gases leaving the furnace, especially when high furnace temperatures are employed around the lower portion of the heating coil in a furnace such as illustrated. Such well known expedients, however, do not form an essential or novel part of the present invention.

As a specific example of the increased efficiency of a furnace such as illustrated and above described, as compared with the usual type of radiant and convection heaters, we will assume two cases.

In the first case, wherein the features of the present invention are not utilized, a single row of radiant roof and wall tubes is employed in the radiant heating section of the furnace and additional heat is recovered by convection from the hot combustion gases before they pass from the furnace by means of a separate bank of convection tubes.

In the second case, wherein the features of the present invention are utilized, the furnace structure is of the type above illustrated and both radiant and convection heating is accomplished in the same tube bank.

The size and spacing of the tubes in the second case is the same as or equivalent to the size and spacing of the tubes in the radiant bank of the first case and the firing conditions are so regulated that in each case about 30,000 B. t. u's. of radiant energy, per square foot of equivalent heat absorbing surface, is available, theoretically, for absorption by the tubes. In the first case approximately 66 per cent of this total is absorbed by that half of the surface of the tubes exposed to direct radiation and approximately 22 percent is absorbed by the other half of the tube surface, making a total of about 26,400 B. t. u's. absorbed in the radiant bank, per projected square foot of tubing or about 8,300 B. t. u's., per circumferential square foot of tubing. In addition about 6,000 B. t. u's. per circumferential square foot of tubing are absorbed by convection in the radiant bank and the convection bank receives an average of about 5,000 B. t. u's. per circumferential square foot of tubing. With about 70 per cent of the total tube surface located in the radiant section of the furnace and about 30 per cent in the convection section, the average rate 70 of heat input for the total fluid conduit is about 11,500 B. t. u's. per hour per circumferential square foot.

In the second case, due to the application of direct radiant heat to opposite sides of each 75

tube of the fluid conduit, about 66 per cent of the 30,000 B. t. u.'s. or thereabouts available per square foot of projected tube surface is absorbed on each half of the tube, giving a total of approximately 39,600 B. t. u.'s. per projected square foot of tube surface as compared with about 26,400 B. t. u.'s. in the first case, or approximately 12,600 B. t. u.'s. per circumferential square foot in the second case as compared with approximately 8,300 in the first. Assuming that about 30 per cent of the total heat input in the second case is by convection, in order to make it comparable to the first case, an additional 5,400 B. t. u.'s. or thereabouts per square foot of circumferential tube surface is absorbed by convection. This gives a total average heat input of about 18,000 B. t. u.'s. per hour per circumferential square foot of tubing in the second case as compared with about 11,500 as above shown in the first case, which is an increase of approximately 52 per cent in favor of the improved method of heating of the present invention.

With firing conditions such that a greater proportion of radiant to convection heating is employed, a still greater percentage increase of the rate of heat input may be accomplished by use of the features of the present invention.

I claim as my invention:

1. In a process for heating fluid of the character wherein the fluid is passed through a conduit of restricted cross section disposed within a heating zone, the improvement which comprises simultaneously subjecting opposite sides of said fluid conduit to superimposed radiant and convection heat whereby to obtain a high average rate of heating around the entire periphery of the conduit while independently controlling the rate of heating at various points along the path of flow of the fluid through the conduit.

2. In a process for heating fluid of the character wherein the fluid is passed through a conduit of restricted cross section disposed within a heating zone, the improvement which comprises uniformly heating opposite sides of said fluid conduit by simultaneously supplying superimposed radiant and convection heat thereto whereby to obtain a high average rate of heating around the entire periphery of the conduit while independently controlling the rate of heating at various points along the path of flow of the fluid through the conduit.

3. In a process for heating fluid of the character wherein the fluid is passed through a conduit comprising a plurality of tubular elements of restricted cross section disposed within a heating zone and forming a continuous fluid passageway, the improvement which comprises simultaneously subjecting opposite sides of each element to superimposed radiant and convection heat whereby to obtain a high average rate of heat around the entire circumference of each element while independently controlling the rate of heating to which different elements of the fluid conduit are subjected.

4. In a process for heating fluid of the character wherein the fluid is passed through a conduit comprising a plurality of tubular elements of restricted cross section disposed within a heating zone and forming a continuous passageway, the improvement which comprises uniformly heating opposite sides of each element by simultaneously supplying superimposed radiant and convection heat thereto whereby to obtain a high average rate of heat around the entire circumference of each element while independently con-

trolling the rate of heating to which different elements of the fluid conduit are subjected.

5. In a process for heating fluid of the character wherein the fluid is passed through a conduit of restricted cross section disposed within a heating zone, the improvement which comprises simultaneously subjecting opposite sides of said fluid conduit to fluid heat from directed streams of hot products of combustion and superimposed radiant heat from radiating surfaces whereby to obtain a high average rate of heating around the entire periphery of the conduit while independently controlling the rate of heating at various points along the path of flow of the fluid through the conduit.

6. In a process for heating fluids of the character wherein the fluid is passed through a conduit comprising a plurality of tubular elements of restricted cross section disposed within a heating zone and forming a continuous fluid passageway, the improvement which comprises simultaneously subjecting opposite sides of each element to fluid heat from directed streams of hot products of combustion and superimposed radiant heat from radiating surfaces, whereby to obtain a high average rate of heating around the entire circumference of each element, while independently controlling the rate of heating to which different elements of the fluid conduit are subjected.

7. In a process for heating fluid of the character wherein the fluid is passed through a conduit comprising a plurality of tubular elements of restricted cross section disposed within a heating zone and forming a continuous fluid passageway, the improvement which comprises uniformly heating opposite sides of each element by simultaneously supplying fluid heat from directed streams of hot products of combustion and superimposed radiant heat from radiating surfaces to said opposite sides, whereby to obtain a high average rate of heating around the entire circumference of each element, while independently controlling the rate of heating to which different elements of the fluid conduit are subjected.

8. An apparatus for heating fluids comprising, in combination, a furnace structure containing a heating zone, a fluid conduit of restricted cross section disposed in said heating zone, combustion zones located on opposite sides of said heating zone, a perforated wall, highly conductive to radiant heat, separating each combustion zone from the heating zone, means for supplying combustible fuel to each combustion zone, means for removing combustion gases from the heating zone whereby opposite sides of the fluid conduit along its entire length in the heating zone are simultaneously subjected to heating by superimposed radiation and convection and means for independently supplying regulated quantities of combustible fuel to various portions of each combustion zone whereby to independently control the rate of heating in different portions of the fluid conduit.

9. An apparatus for the heating of fluids comprising in combination a furnace structure containing a heating zone, a fluid conduit disposed in said heating zone and comprising a plurality of tubular elements connected in series, combustion zones located on opposite sides of said heating zone, a perforated wall, highly conductive to radiant heat, separating each combustion zone from the heating zone, from which walls and through which perforations therein radiant heat is transmitted to opposite sides of each element of the fluid conduit, and through which perfora-

tions combustion gases are directed from the combustion zones into the heating zone to simultaneously supply fluid heat to opposite sides of each element of the fluid conduit, means for removing combustion gases from the heating zone, and means for independently supplying regulated quantities of combustible fuel to various portions of each combustion zone whereby to independently control the rate of heating in different elements of the fluid conduit.

10. In a process for heating fluid of the character wherein the fluid is passed through a conduit of restricted cross-section disposed within a heating zone, the improvement which comprises uniformly heating opposite sides of said fluid conduit by fluid heat from directed streams of hot products of combustion and superimposed radiant heat from radiating surfaces whereby to obtain a high average rate of heating around the entire periphery of the conduit while independently controlling the rate of heating at various points along the path of flow of the fluid through the conduit.

11. In a process for heating fluid of the character wherein the fluid is passed through a conduit of restricted cross section disposed within a heating zone, the improvement which comprises simultaneously subjecting opposite sides of said fluid conduit to heat of substantially equal intensity whereby to obtain a high average rate of heating around the entire periphery of the conduit and controlling the amount of heat applied at various points along the path of flow of fluid through the conduit.

12. In a process for heating fluid of the character wherein the fluid is passed through a conduit of restricted cross section disposed within a heating zone, the improvement which comprises uniformly heating opposite sides of the said fluid by simultaneously supplying thereto heat of substantially equal intensity to obtain a high average rate of heating around the entire periphery of the conduit, and controlling the rate of heating at various points along the path of flow of the fluid through the conduit.

13. In a process for heating fluid of the character wherein the fluid is passed through a conduit comprising a plurality of tubular elements of restricted cross section disposed within a heating zone and forming a continuous fluid passageway, the improvement which comprises simultaneously subjecting opposite sides of each element to heat of substantially equal intensity whereby to obtain a high average rate of heating around the entire circumference of each element, and independently controlling the amount of heat to which certain elements of the fluid conduit are subjected.

14. In a process for heating fluid of the character wherein the fluid is passed through a conduit comprising a plurality of tubular elements of restricted cross section disposed within a heating zone and forming a continuous passageway, the improvement which comprises uniformly

heating opposite sides of each element by simultaneously supplying thereto heat of substantially equal intensity whereby to obtain a high average rate of heating around the entire circumference of each element, and independently controlling the rate of heating to which certain elements of the fluid conduit are subjected.

15. In a process for heating fluid of the character wherein the fluid is passed through a conduit of restricted cross-section disposed within a heating zone, the improvement which comprises simultaneously subjecting opposite sides of said fluid conduit to heat of substantially equal intensity and controlling the amount of heat applied at various points along the path of flow of fluid through the conduit to thereby secure any desired predetermined heating curve for the fluid passing through the heating zone and controlling the heating curve dependent upon the character of the fluid being heated.

16. In a process for heating fluid of the character wherein the fluid is passed through a conduit of restricted cross-section disposed within a heating zone, the improvement which comprises simultaneously subjecting opposite sides of said fluid conduit to heat of substantially equal intensity and modifying, at a point along the path of flow of fluid through the conduit, the amount of heat applied thereto to thereby secure a predetermined heating curve for the fluid flowing through said conduit and to controllably vary the rate of heat input to the fluid as it advances through the conduit.

17. In a process for heating fluid of the character wherein the fluid is passed through a conduit of restricted cross-section disposed within a heating zone, the improvement which comprises simultaneously subjecting opposite sides of said fluid conduit to heat of substantially equal intensity and modifying, at predetermined points along the path of flow of fluid through the conduit, the amount of heat applied thereto to thereby progressively vary the rate of heat input to the fluid as it advances through the conduit to secure a predetermined heating curve for the fluid being heated.

18. A process for heating fluid in a heating coil embracing serially-connected tubular elements disposed substantially in a common plane intermediate and in unobstructed heat radiating relation to heat radiating walls substantially parallel to said plane, comprising generating flame in combustion zones on opposite sides of said coil at a plurality of spaced points therein and directing the same toward said walls so as to impart incandescence to a substantial portion thereof, and so controlling the generation of flame in said combustion zones that heat of substantially uniform intensity embracing direct heat from combustion gases and heat radiated from said incandescent walls is applied to opposite sides of any given tubular conduit embraced in said heating coil.

JOSEPH G. ALTHER.
